AIRPLANE

Filed Jan. 11, 1928

Inventor
VINCENT J. BURNELLI

By his Attorney
Frederick W. Barker

UNITED STATES PATENT OFFICE

VINCENT J. BURNELLI, OF NEW YORK, N. Y., ASSIGNOR TO THE UPPERCU-BURNELLI CORPORATION, A CORPORATION OF DELAWARE

AIRPLANE

Application filed January 11, 1928. Serial No. 245,857.

This invention relates to airplanes of the all wing type and my improvements are directed to certain novel and useful structures and arrangements of parts whereby the efficiency and serviceability of such airplanes may be increased.

Briefly my said improvements may be summarized as follows:

(1) The location of motors between the front and rear spars within an airfoil contour.

(2) The provision of a box-like motor mount composed of longitudinals and trussed bracing extended between the front and rear spars.

(3) The provision of an extension housing for the propeller shaft that extends through the airfoil entering edge, said housing being bolted to a vertical web disposed longitudinally in the airfoil nose.

(4) The provision of openings through the walls separating a central airfoil from side airfoils to enable access to be had from said central airfoil to the engines in the side airfoils.

(5) The suspension of a cabin beneath the airfoil in the region of the front spar, for occupation by the pilot, navigator, bomber or passengers, said cabin having windows at its front, rear and sides to permit range of vision laterally and downwardly, upward clearance means permitting access and view into the airfoil interior.

Other features and advantages of my invention will hereinafter appear.

In the drawings:

Figure 1 is a front elevation of an airplane embodying my improvements.

Fig. 2 is a side elevation of said airplane in a smaller scale, and

Fig. 3 is a side view partly in section.

In said views let 1 indicate an airfoil having engines, indicated at 2, mounted in the nose portion thereof, in advance of the front spar 3, the interior of said nose portion being designated the engine room, and passenger accommodation located in an intermediate portion of the airfoil extended from the front spar 3 and the rearward spar 4, said

accommodation being designated the passenger saloon.

The motors 2 respectively operate propellers 5 whose shafts are extended out from the airfoil entering edge through housings 6.

In the example of my improved airplane illustrated in the drawing smaller airfoils 7 are shown as extended from the sides of a larger, central airfoil, though I do not limit myself to this particular structure as my invention equally comprehends the use of a single airfoil of considerable span, having a conterminous entering edge.

Since the airfoils 7 at opposite sides of central airfoil 1 are alike, the description of one equally applies to the other.

Thus the front and rear spars 8 and 9 in airfoils 7 are located respectively in the same transverse planes as spars 3 and 4, being in fact continuations thereof. Intermediate spars 8 and 9 and connected therewith are the longitudinals 10 constituting the mount for motor 11, said mount being reinforced by trussing 12 which is also connected with spars 8 and 9. Angled frames 13, connected with spar 8 and also engaging the mount 11, serve to further reinforce the supporting means therefor.

Extended forwardly from the front spar 8 and projecting through the nose or leading edge 14 of airfoil 7 is a housing 15 for the shaft 16 of propeller 17. Said housing is formed in two parts having flanges 18 that are bolted to vertical webs 19 which in turn are bolted to a rib flange 20 within the nose portion 14.

Angle members 21, secured to the spar 8 and also engaging the housing 15, further reinforce the supporting means for said housing.

An opening 22 is provided through the wall 23 separating the interiors of airfoils 1 and 7 to enable access to be had to motor 11.

Attached to the underside of airfoil 1 is a cabin structure 24, of stream-lined form, located beneath the front spar 3, the airfoil bottom being apertured above said cabin to provide means of observation from the cabin into the engine compartment forwardly of spar 3 and into the interior of airfoil 1 rear-

wardly of said spar, where there may be passenger accommodation. Also by means of said airfoil bottom being apertured communication can be had between said cabin and the interior of said airfoil.

As the depth of cabin 24 may be limited so that a pilot seated therein would have insufficient head room with respect to spar 3, I may provide a clearance, indicated at 25, in the under surface of said spar. The cabin is provided all around its walls with windows 26, thus affording the pilot, and others located therein a range of vision that is not available from any other centrally located cockpit or observation space in an all wing airplane of previously known design.

This application is a continuation in part of my application Serial No. 435,481, filed January 6, 1921.

Variations within the spirit and scope of my invention are equally comprehended by the foregoing disclosure.

I claim:—

1. The combination with an airfoil having a forward spar and a motor disposed rearward of said spar, of a housing for the propeller shaft that extends through and beyond the leading edge of said airfoil, and bracing means for said housing within said leading edge.

2. In an all wing airplane having a central supporting airfoil section of full length, and lateral supporting airfoils, of shorter chord, extending from opposite sides of said central section, the combination of front and rear spars that are extended continuously through said central section and said airfoils of shorter chord, longerons constituting a motor mount located wholly between said spars and connected therewith, and truss reinforcement for said longerons extending between said longerons and the lower surface of the airfoil and also connected with said spars.

3. In an all wing airplane having a central supporting airfoil section of full length, and lateral supporting airfoils, of shorter chord, extending from opposite sides of said central section, the combination of front and rear spars that are extended continuously through said central section and said airfoils of shorter chord, longerons constituting a motor mount located wholly between said spars and connected therewith, and angled frames connected with the top and bottom of one of said spars and said longerons.

4. The combination with an airfoil having an interior spar, of a motor mount in said airfoil, located forwardly of said spar, a motor upon said mount, a cabin structure attached to and depending from the bottom of said airfoil, beneath said spar and extended both forwardly and rearwardly thereof, said cabin structure containing the motor control means, and adapted for occupancy

with lookout means and means of observation between said cabin and the airfoil interior.

New York, December 28th, 1927.

VINCENT J. BURNELLI.
